(57) **CLAIM**

The ornamental design for a grip for a pet leash, as shown
and described.

DESCRIPTION

FIG. 1 is a front, top, right side perspective view of a grip
for a pet leash showing our new design;

FIG. 2 is a top plan view thereof, the bottom plan view being
a mirror image of FIG. 2;

FIG. 3 is a left side elevational view thereof, the right side
elevational view being a mirror image of FIG. 3;

FIG. 4 is a rear elevational view thereof; and,

FIG. 5 is a front elevational view thereof.
